DESIGN FOR A CABINET FOR A COMPUTING MACHINE OR SIMILAR ARTICLE

Max Garbell, Los Angeles, Calif.

Application July 30, 1945, Serial No. 121,062

Term of patent 14 years

(Cl. D64—11)

To all whom it may concern:

Be it known that I, Max Garbell, a citizen of the United States, residing in Los Angeles, in the county of Los Angeles, State of California, have invented a new, original, and ornamental Design for a Cabinet for a Computing Machine or Similar Article, of which the following is a specification, reference being had to the accompanying drawings forming a part thereof.

Figure 1 is a perspective view of a cabinet for a computing machine, showing my novel design.

Figure 2 is a side view of the same.

Figure 3 is a top view of the same.

Figure 4 is a rear view of the same.

The essential parts of the design are shown in full lines.

I claim:

The ornamental design for a cabinet for a computing machine or similar article, as shown and described.

MAX GARBELL.
